Emil Mechau

UNITED STATES PATENT OFFICE.

EMIL MECHAU, OF RASTATT, GERMANY.

MOTION-PICTURE-PROJECTING APPARATUS.

Application filed September 19, 1922. Serial No. 589,200.

To all whom it may concern:

Be it known that I, EMIL MECHAU, a citizen of the Republic of Germany, residing at Rastatt, Germany, have invented certain new and useful Improvements in Motion-Picture-Projecting Apparatus (for which I have filed an application in Germany October 10, 1921), of which the following is a specification.

10 My invention relates to improvements in motion-picture-projecting apparatus in order to prevent the film from fire, and in which a device is employed for protecting the film against the beam of light before it gets ignited. This device may be of any suitable kind provided that it is adapted to interrupt the access of the beam of light to the film in a given moment.

15 The general object of my invention is to provide very simple and reliable means in such apparatus for actuating the protecting device, and which means may be employed in combination with various known motion-picture-projecting apparatus so that 20 my invention may be added to various existing apparatus to effect the desired prevention from fire.

25 My invention consists of a member which is adapted to swim on a fluid and to engage with the mentioned device for protecting the film against the beam of light, and of a feeding device which can be set in action by suitable means, for instance by the film driving gear or by a roll driven 30 from the moving film. When the speed of the film through the apparatus is above a predetermined value, this feeding device draws up more fluid under the floating member than can flow back, whereupon the 35 floating member falls and thereby sets the device for protecting the film against the beam of light out of operation. Similarly when the speed of the film through the apparatus is below this predetermined value, 40 the feeding device draws up less fluid, whereupon the floating member rises again and thereby sets the projecting device into operation.

45 The fluid drawn up may either be fed 50 by the feeding device into an adjacent chamber or applied as a weight on to the floating member. The latter arrangement ensures a high security especially if the fluid is a heavy one as for instance quicksilver.

55 I have shown in the drawing one specific form of apparatus embodying my inven-

tion, but I desire to be understood that my invention, as set forth in the annexed claims, is not dependent of any particular projecting apparatus or of the exact details 60 of construction shown and described, for obvious modifications will occur to a person skilled in the art.

Figure 1 is a section of so much of a motion-picture-projecting apparatus as is necessary to show my improvements, and 65

Figure 2 is a perspective view of the same.

Referring to the figures, especially to Figure 1, the dotted line A B C D lets 70 show the path of rays of light through the apparatus. A source of light emitting a beam of light to illuminate a film 1 is to be thought to the left of an opening 2 which can be closed by means of a shutter 3 mounted on a bent lever 4, the latter being movable about a shaft 5. A spiral spring 6 is connected to the bent lever 4 in such a manner that the shutter 3 tends always to close the entrance opening 2 for the illuminating beam of light. On the upper end of the bent lever 4 is fitted an arm 7 having a hook formed end.

75 In an entirely closed chamber 8 filled partly with quicksilver a paddle wheel 9 is placed revoluble about an axis 10 on which is also fixed a roll 11. This roll 11 and consequently the paddle wheel 9 is set into rotation by the film 1 moving through the projector gate of the apparatus. Further 80 in the chamber 8 is situated a sheave 12 with a shaft 13, the latter being guided in such a manner that the sheave 12 is only movable in the direction of its shaft 13. The sheave 12 will swim on the quicksilver 85 by stopping paddle wheel 9; if the latter by moving film 1 rotates, it draws up quicksilver under the sheave 12 and brings it up to the same. Of this quicksilver a part flows back on the walls surrounding the sheave 90 12 and another part returns through an opening provided in the sheave 12, the opening being made of such a greatness that by a given speed of the film 1 (and consequently of the paddle wheel 9) as much quicksilver is drawn up under the sheave 12 as flows back. By increasing speed the sheave 12 will fall and by diminishing speed it will rise. By means of a projecting part 14

95 fixed on the shaft 13 is effected that the 100 sheave 12 cannot fall to the bottom of the chamber 8, and by a given speed of the pad-

idle wheel 9 an air space is produced between the sheave 12 and the quicksilver being at the bottom of the chamber 8.

At the lower end of the shaft 13 is flexibly fitted an arm 15 which is connected with a rotatable axis 16 bedded in a wall of the chamber 8 and passing outside the same, where on the axis 16 a catch 17 is fixed capable to cooperate with the hook formed end 10 of the arm 7. As easily to recognize, the arm 15 and the catch 17 form together a lever adapted to be actuated by the shaft 13.

By beginning the projection the bend lever 4 with the shutter 3 is so holden by hand that the opening 2 becomes free for the beam of light illuminating the film 1. Already after a few moments of operation the paddle wheel 9 will have drawn up so much quicksilver under the sheave 12 that the latter falls and the catch 17 can engage with the hook formed end of the arm 7, thereby by means of the bent lever 4 preventing the shutter 4 to close the opening 2. If for any reason the film 1 stops and would consequently get ignited, the paddle wheel 9 will also stop thereby causing the sheave 12 and the catch 17 which is connected with it to rise, so that the end of the arm 7 becomes free and the shutter 3 will fall owing 30 to the spring 6 hereby closing the opening 2, as sketched in Figure 1 in dotted lines.

Having thus described my invention, what I claim and desire to secure by Letters Patent is:

- 35 1. In a motion-picture projecting apparatus in combination, means for protecting the film against the beam of light, a reservoir, a fluid in the reservoir, a member adapted to swim on the fluid and to engage with said means for protecting the film, a device for drawing up fluid under the said member, means for reconducting to the reservoir the fluid drawn up, and means for driving the said drawing device.
- 45 2. In a motion-picture projecting apparatus in combination, means for protecting the film against the beam of light, a reservoir, a fluid in the reservoir, a member adapted to swim on the fluid and to engage with said means for protecting the film, a device for drawing up fluid under the said member and for feeding it up as a weight on to the said member, means for reconducting to the reservoir the fluid drawn up and fed on, and means for driving the said drawing device.

3. In a motion-picture projecting apparatus in combination, means for protecting the film against the beam of light, a reservoir, a fluid in the reservoir, a member adapted to swim on the fluid and to engage with said means for protecting the film, a device for drawing up fluid under the said member and for feeding it up as a weight on to the said member, means for reconducting to the reservoir the fluid drawn up and fed on, and a film roll for driving the said drawing device.

4. In a motion-picture projecting apparatus in combination, a shutter device for protecting the film against the beam of light, a reservoir, a fluid in the reservoir, a member adapted to swim on the fluid and to engage with said shutter device, a device for drawing up fluid under the said member and for feeding it up as a weight on to the said member, means for reconducting to the reservoir the fluid drawn up and fed on, and a film roll for driving the said drawing device.

5. In a motion-picture projecting apparatus in combination, means for protecting the film against the beam of light, a reservoir, quicksilver in the reservoir, a member adapted to swim up the quicksilver and to engage with the said means for protecting the film, a device for drawing up quicksilver under the said member and for feeding it up as a weight on the said member, means for reconducting to the reservoir the quicksilver drawn up and fed on, and means for driving the said drawing device.

6. In a motion-picture projecting apparatus in combination, a shutter device for protecting the film against the beam of light, a reservoir, quicksilver in the reservoir, a member adapted to swim up the quicksilver and to engage with the said shutter device, a rotating paddle wheel for drawing up quicksilver under the said member and for feeding it up as a weight on to the said member, means for reconducting to the reservoir the quicksilver drawn up and fed on, and a film roll for driving the paddle wheel.

In testimony whereof I have signed my name to this specification.

EMIL MECHAU. [L.s.]
In the presence of—

VIKTOR BENDER,
OTTO WAGNER.
